UNITED STATES PATENT OFFICE.

GEORGE THOMAS PRITCHARD, OF NORFOLK, VIRGINIA.

ENVELOPE MOISTENER AND SEALER.

Application filed April 22, 1924. Serial No. 708,212.

This invention relates to envelope moisteners and sealers.

The object is to provide a simple, strong and durable device to be operated by hand, for moistening and sealing the flaps of envelopes of various sizes so as to expedite the operation of handling mail matter.

Another object is to provide a device for this purpose which may be cheaply manufactured and sold at a low cost, the device being formed principally of sheet metal stamped and bent into shape to provide means for engaging the flap of an inverted envelope, and directing the same up and over a moistened pad so as to moisten the adhesive-coated inner face only of the flap, the envelope proper being protected from such moisture, then directing said flap back onto the envelope again and bringing pressure to bear thereon to cause the moistened adhesive to adhere to the envelope and to seal the same, the entire operation being accomplished by a single stroke or passage of the device across the envelope in a longitudinal direction.

Another object is to provide means for constantly supplying moisture to the said pad, such means being in the form of a water container which may be readily detached for filling the same, and means connected therewith for conducting the water by capillary attraction to the pad without leakage thereof, said pad being readily removable from the device for cleansing or renewal.

A final object is to provide means for pressing the flap onto the moistening pad as the device slides over the envelope without danger of tearing the said flap, said means being in the form of a presser foot detachably connected to the frame of the device, so as to permit the removal of the said pad.

A full and complete understanding of the invention may be obtained from a consideration of the following description, taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:

Figure 1 is a perspective view of the device in the operation of moistening and sealing an envelope.

Figure 2 is an enlarged plan view, partly in section, the presser foot being removed to more fully disclose the envelope flap.

Figure 3 is an inverted plan view of the device, and illustrating the relation of the envelope flap thereto.

Figure 4 is a longitudinal sectional view of the device.

Figure 5 is a vertical sectional view taken on the line 5—5 of Figure 2 and looking in the direction of the arrows.

Figure 6 is a similar view taken on the line 6—6 of Figure 2 and looking in the direction of the arrows.

Figure 7 is a similar view taken on the line 7—7 of Figure 4 and looking in the direction of the arrows.

Figure 8 is a detail sectional view illustrating the means for deflecting the envelope flap.

Referring to the drawings there is shown a base member 1 which is formed of suitable sheet metal, preferably brass, so as to avoid corrosion or rusting. The base 1 is elongated, being substantially the shape of a large sized envelope, and is provided along each longitudinal side edge with an upstanding flange 2, formed by bending the metal, said flange serving to stiffen or strengthen the base and prevent bending or buckling the same while in operation.

At each end, the base member 1 is bent upwardly and rounded as at 3 to permit the device to be drawn by hand lengthwise over the envelopes without danger of catching the ends of the same. The upturned ends 3 of the base have integrally formed, centrally disposed, upstanding arms 4, arranged in longitudinal alignment with each other and suitably apertured for the reception of fastening means for a handle 5, preferably formed of round wood and extending the full length of the base. The handle is spaced above the base member to be readily grasped by the hand of the operator without danger of the fingers interfering with certain parts carried by the base.

In sealing an envelope, as indicated at E in Fig. 1 of the drawing, the device is adapted to be placed near one end thereof.

and arranged longitudinally of the same to be passed in that direction thereover, as indicated by the arrow in said figure, the righthand side edge of the base having the 5 upturned flange 2 thereon preferably overlying the edge of the envelope having the flap F connected thereto, and with said flap lying flat upon the envelope as in normal condition. The upturned and rounded front 10 end 3 of the base thus serves to ride the said base over the edge of the envelope and the flap without danger of catching on and tearing the same.

Somewhat in rear of the front end 3, the 15 base 1 is provided with a diagonally disposed slot 6 extending from a point adjacent to the lefthand reinforcing flange 2, rearwardly and across to a point between the central longitudinal line of the base and the 20 righthand flange 2, where the metal of the base is cut away to provide a longitudinal opening 7. At the rear end this opening 7 communicates with a triangular, transverse slot 8, the rear edge of which is diagonally disposed to the base and opposite to the direction of the aforesaid slot 6, as clearly shown in Figures 2 and 3 of the drawings. The metal of the base thus defined between the front slot 6 and the opening 7 and slot 8 25 is formed into a front tongue 9 and a rear tongue 10 by means of a slot 11 extending transversely of the base and communicating with the aforesaid opening 7. The tongues 9 and 10 each have a free end and are joined 30 at the lefthand side to the base.

The slot 6 preferably widens somewhat towards the free end of the tongue 9, and the forward, diagonal edge of the latter is bent slightly downward as at 12 to insure 35 engagement beneath the flap F of the envelope when the device is passed over the latter as indicated, and likewise the rear diagonal edge of the slot 8 is provided with an upturned and curved flange 13 for the 40 purpose of directing the said flap downwardly again, as will become apparent. For the purpose of stiffening the base where provided with the several openings and slots, an upturned flange 14 is provided at the 45 outer or righthand edge of the longitudinal opening 7, said flange being inclined and rounded to prevent damaging the flap 8.

The rear tongue 10 is elevated slightly above the plane of the base 1 by transversely bending the same where joined to said base as at 15 and the rear edge of the front tongue 9 is likewise bent upwardly throughout its length to provide a seat 16 for a purpose to be explained.

60 A pad 17, preferably formed of felt or some other suitable absorbent material, is mounted on the rear tongue 10 and extends from the free end of the latter into abutting relation with the lefthand reinforcing flange 2, the outer end of the pad being

turned upwardly, as at 18, and the said flange having an upwardly extended wall 19 to fit against said end 18 of the pad. Interposed between the wall 19 and the end 18 of the pad is a thin sheet of celluloid 20, or 70 some other moisture proof material, which may be sewed or otherwise secured to the end 18 of the felt pad, and which is provided to prevent moisture passing through the pad from contacting with the wall 19. 75

In order to secure the pad 17 to the supporting tongue 10, a sheet of similar moisture proof material 21 is sewed around two of its sides and at the end to the felt pad 17, thus forming a pocket between the same 80 to be slipped over the free end of the tongue, the aforesaid opening 7 providing ample space for such operation. The celluloid or other sheet 21 is somewhat wider than the supporting tongue and finds lodgment at the 85 front edge, in the aforesaid seat 16, and the lower face of said sheet is substantially on a plane with the lower face of the base member 1, by reason of the fact that the tongue 10 is bent upwardly, at 15, as before stated. 90

The rear end of the lefthand stiffening flange 2 is provided with an inwardly directed stop finger 22, preferably formed integrally therewith, and somewhat in advance of the same, the said flange is further 95 provided with an overhanging, spring clip 23, also formed integrally therewith and disposed in the arc of a circle.

The clip 23 is adapted to hold a small phial 24 containing water, the closed end of 100 the same abutting against the stop finger 22, and having at its front end a suitable screw closure 25 adapted to permit filling the phial and also to prevent leakage when screwed thereon. The closure 25 is provided with a 105 suitable opening for the entrance of a wick 26 formed of suitable absorbent material, preferably felt, and having one end located near the closed end of the phial, and the other extending to and along the aforesaid 110 wall 19, and between the same and the aforesaid upturned end 18 of the pad 17, so that water contained in the phial will find its way, by capillary attraction, through the wick to the upturned end of the pad, and 115 thence throughout the latter to be applied to the adhesive inner face of the flap of the envelope. That face of the wick 26 directed toward the center of the base member is 120 preferably covered with a sheet 27 of celluloid in the same manner as the outer face of the upturned end of the pad. A metal or other container may be used in lieu of the phial 24, though the glass phial is preferable as the amount of water contained 125 therein may always be ascertained at a glance.

A presser foot 28 of a size and shape to substantially cover the pad 17 is adapted to bear at all times upon the same, the said 130

presser foot being in the form of a plate and made of sheet metal similar to the base member, and having along its lefthand edge an upturned wall or flange 29 which bears against the inner face of the aforesaid strip or sheet 27 of non-absorbent material 27, attached to the inner face of the wick and holds the latter tightly against the upturned end of the pad.

10 The plate constituting the presser foot 28 is joined to a forwardly and upwardly curved, spring arm 30 having at its end an integrally formed cross head 31, the lower edges of the extending portions of which 15 are adapted to be seated in hooks 32 formed on the top edge of the upturned end 3 of the base, and at each side of the upstanding arm 4 at the front end of said base. The top edge of the cross head is adapted to be snapped or pressed beneath a pair of rearwardly extending lugs 33 formed on the side edges of said arm 4, and when the said cross head is thus secured the downward tendency 20 of the spring arm 30 serves to press the plate 28 against the pad 17 beneath the same with sufficient force to positively hold the flap F of the envelope in direct contact with the felt pad, and thus becomes thoroughly wetted or moistened during the passage of 25 the same thereover.

With the pad secured in place on the tongue 10, and with the upturned end 18 of the pad held or clamped in close contact with the wick between the wall 19 of the base and the wall or flange 29 of the presser foot, the rear end of the wick being within the container and the latter filled with water, the device is applied to the inverted envelope as before stated. The downwardly directed edge 12 of the tongue will be caused to engage the inclined edge of the flap F as the device is moved forwardly by one hand of the operator, with the right-hand edge of the device overhanging the top 40 or flap edge of the envelope, while the latter is being held by the other hand of the operator. The flap is directed upwardly through the slot 6 as the device is moved, and passes beneath the presser foot 28 which holds the underside of the flap having the adhesive f thereon (see Figure 3) in close contact with said pad. The flap is then drawn down through the rear opening 8, the advance portion of the rounded flange 13 thus directing the flap, and the rear flat portion of the base member 1 in sliding over the flap, which now lies upon the envelope, causes the same, under the pressure of the hand, to adhere to the envelope.

60 The device is especially useful where a large quantity of letters require moistening and sealing, and in time great rapidity may be attained thus expediting and making easy, an otherwise unpleasant and time-consuming operation.

From the foregoing it will be seen that a simple and cheaply constructed device for moistening and sealing envelopes has been provided, and that the same may be used on envelopes of different kinds and sizes, 70 no especial care being required to direct or guide the device over the envelope to properly moisten and seal the same, and that ample provision has been made to prevent tearing the flap or wetting or damaging 75 the envelope in any manner, the moisture being applied only where needed, and that with one movement of the hand, while the other hand holds the envelope, the entire 80 operation is performed.

What is claimed is:—

1. An envelope moistener and sealer, comprising a base, a handle supported above the base, means provided in the base for raising the flap of an envelope, a transversely disposed tongue on the base, a moistening pad having moisture-proof material attached thereto and forming a pocket to be slipped over the free end of said tongue, said pad being adapted to be passed beneath the envelope flap, and pressing means located over the pad for engaging the flap and pressing the latter upon the pad as the device is drawn across the envelope. 85

2. An envelope moistener and sealer comprising an elongated base, a longitudinally disposed handle supported over the base and connected thereto, a transversely disposed tongue formed integrally with the base and having its forward edge bent 100 downwardly and adapted to engage beneath and lift the flap of an inverted envelope, a moistening pad carried by the base in rear of the tongue in a position to pass between the flap and the envelope as the device is 105 drawn across the same to moisten said flap, a spring presser foot of a size and shape to substantially cover the pad and adapted to bear on the same for holding the flap onto the pad, and means for guiding the moistened flap onto the envelope and pressing the same thereon at the end of the stroke. 110

3. An envelope moistener and sealer adapted to be drawn across an inverted envelope, comprising a base, a handle secured to said base, spaced tongues formed in the base and arranged transversely thereof and each having a free end, one of said tongues having its free end depressed below the plane of the base and adapted to lift the flap of 120 an envelope and direct the same over the other tongue, and a pad carried by the latter tongue for moistening the adhesive on said flap. 115

4. An envelope moistener and sealer adapted to be drawn across an inverted envelope, comprising a base having its ends curved upwardly and terminating in upstanding arms, a longitudinally disposed handle secured to said arms, spaced tongues 125

formed in the base and arranged transversely thereof and each having a free end, one of said tongues having its free end depressed below the plane of the base and 5 adapted to lift the flap of an envelope and direct the same over the other tongue, and a pad carried by the latter tongue for moistening the adhesive on said flap.

5. An envelope moistener and sealer 10 adapted to be drawn across an inverted envelope, comprising a base having its ends curved upwardly and terminating in upstanding arms, a longitudinally disposed handle secured to said arms, spaced tongues 15 formed in the base and arranged transversely thereof and each having a free end, one of said tongues having its free end depressed below the plane of the base and adapted to lift the flap of an envelope and 20 direct the same over the other tongue, a pad carried by the latter tongue for moistening the adhesive on said flap, means for supplying moisture to the pad by capillary attraction, and a spring presser foot bearing on 25 the pad to hold the said flap in contact therewith.

6. A hand operated envelope moistener and sealer comprising an elongated base, a handle mounted above the base for drawing 30 the same longitudinally across an inverted envelope, said base having a pair of transversely disposed tongues intermediate its ends and formed integrally with the base, one of said tongues being adjacent to 35 one end of the base and having its outer edge angularly disposed and depressed to engage beneath the flap of the envelope and lift the same, the other tongue having a moistening pad mounted on the upper face 40 thereof to contact with the adhesive on said flap, and means for maintaining the pad in a moist condition.

7. A hand operated envelope moistener and sealer comprising an elongated base, a handle mounted above the base for drawing 45 the same longitudinally across an inverted envelope, said base having a pair of transversely disposed tongues intermediate its ends and formed integrally with the base, one of said tongues being adjacent to one 50 end of the base and having its outer edge angularly disposed and depressed to engage beneath the flap of the envelope and lift the same, the other tongue having a moistening pad mounted on the upper face thereof to contact with the adhesive on said flap, said pad being adapted to slip onto the free end 55 of the supporting tongue and comprising an absorbent upper layer for moistening the flap and a marginally-connected non-absorbent lower layer beneath the tongue to avoid moistening the envelope, and means for 60 maintaining the pad in a moist condition.

8. A hand operated envelope moistener 65 and sealer comprising an elongated base, a

handle mounted above the base for drawing the same longitudinally across an inverted envelope, said base having a pair of transversely disposed tongues intermediate its ends and formed integrally with the base, one of said tongues being adjacent to one 70 end of the base and having its outer edge angularly disposed and depressed to engage beneath the flap of the envelope and lift the same, the other tongue having a moistening pad mounted on the upper face thereof to contact with the adhesive on said flap, means for maintaining the pad in a moist condition, said pad having an upturned extension adjacent to one of the longitudinal 75 edges of the base, said edges having upturned flanges, an upstanding wall formed on the adjacent flange, an absorbent feeding wick bearing against the wall and contacting with the upturned extension of the pad, and means for supplying moisture to the feeding wick and through the same to the pad.

9. A hand operated envelope moistener and sealer comprising an elongated base, a handle mounted above the base for drawing the same longitudinally across an inverted envelope, said base having a pair of transversely disposed tongues intermediate its 90 ends and formed integrally with the base, one of said tongues being adjacent to one end of the base and having its outer edge angularly disposed and depressed to engage beneath the flap of the envelope and lift the same, the other tongue having a moistening pad mounted on the upper face thereof to contact with the adhesive on said flap, means for maintaining the pad in a moist condition, said pad having an upturned extension adjacent to one of the longitudinal 95 edges of the base, said edges having upturned flanges, an upstanding wall formed on the adjacent flange, an absorbent feeding wick bearing against the wall and contacting with the upturned extension of the pad, 100 spring clips carried by said flange, a water container adapted to be sprung into the clips and to lie against the inner face of the flange, and a closure for the container to prevent leakage and having an opening for the feeding wick to constantly supply the pad with moisture.

10. A hand operated envelope moistener and sealer comprising an elongated base, an operating handle supported at its ends above 120 the base, said base having rounded, upturned ends to facilitate passage longitudinally over an inverted envelope, a tongue projecting below the base to engage and lift the flap of the envelope, another tongue carried by the base, a pad supported on the upper face of the second tongue, means for supplying moisture to the pad, means for pressing the flap down upon the pad as the device is drawn across the envelope, and 125

means for guiding the flap back onto the envelope to be pressed thereto by the rear end of the base.

11. A hand operated envelope moistener and sealer comprising an elongated base adapted to be drawn longitudinally over an inverted envelope, said base having an angular slit for the entrance of the flap of the envelope and permitting the same to traverse the upper face of the base for a distance, means for moistening the adhesive side of the flap during such transit, said base having a rear opening the rear edge of which is at an angle opposite to the slit and provided with a curved upturned flange for directing the moistened flap back onto the envelope to be pressed thereto by the passage of the rear portion of the base.

12. A hand operated envelope moistener and sealer comprising an elongated base adapted to be drawn longitudinally over an inverted envelope, upstanding arms formed at each end of the base, an operating handle connected to the upper ends of the arms, said base having an entrance slit near one end, the rear edge of the slit being depressed to lift the flap, and an outlet opening near the center to permit the flap to pass beneath the base again to be pressed onto the envelope, a moistening pad between the slit and the opening to wet the underside of the flap, and a presser foot mounted over the pad to press the flap thereto, said presser foot comprising a plate substantially covering the pad and having an outwardly and upwardly curved spring extending to the adjacent handle arm of the base, said spring having a cross head, lugs carried by the said arm and adapted to interlock with the cross head to detachably hold the presser foot in position over the pad.

13. A hand operated envelope moistener

and sealer comprising a base having a handle mounted thereover, said base having an angular entrance slit for the flap of the envelope and an oppositely angular exit opening therefor, that portion of the base between the slit and the opening being formed into two tongues having inner free ends, the first tongue having its front angular edge depressed to engage said flap, a moistening pad mounted on the second tongue for wetting the flap passing thereover prior to passage downward and out of the opening.

14. A hand operated envelope moistener and sealer comprising a sheet metal base having longitudinal side flanges, a handle mounted thereover, said base having an angular entrance slit for the flap of the envelope and an oppositely angular exit opening therefor, that portion of the base between the slit and the opening being formed into two tongues having inner free ends, the first tongue having its front angular edge depressed to engage said flap, a moistening pad mounted on the second tongue for wetting the flap passing thereover prior to passage downward and out of the opening, said pad having an upturned extension adjacent to the base flange, an upright wall carried by said flange for backing the pad extension, a water container detachably held to the base and having a wick contacting with the pad extension for feeding water to the pad, and a presser plate resiliently mounted on the base to bear on the pad and having an upright wall to hold the free end of the wick against the pad extension.

In testimony that I claim the foregoing as my own, I have hereto affixed my signature.

GEORGE THOMAS PRITCHARD.
